UNITED STATES PATENT OFFICE.

PAUL L. MATHEWS AND RICHARD M. WILLIS, OF NEWARK, NEW JERSEY.

APPARATUS FOR MIXING.

Application filed November 19, 1920. Serial No. 425,257.

To all whom it may concern:

Be it known that we, PAUL L. MATHEWS and RICHARD M. WILLIS, citizens of the United States, and residents of Newark, in the county of Essex and State of New Jersey, have jointly made certain new and useful Improvements in Apparatus for Mixing, of which the following is a specification.

An object of the invention is to provide an apparatus or machine for the mixing, agglomerating, commingling or fluxing of admixtures, such as oil, water, pitch or other materials when in fluid, liquid or semi-liquid form, with another substance or substances suitably prepared for treatment in the machine. One of the substances which the machine is particularly adapted to operate upon is coal residue, preferably a uniformly but partially distilled coal residue or partially carbonized coal, to which pitch for binding purposes is added in the making of briquets. During the mixing and agglomerating, steam, preferably superheated steam, is added to facilitate the fluxing of the materials.

The apparatus is applicable to operate not only upon partially distilled coal, but upon raw coal, coal residues and even upon other materials where it is desired to mix there-with any desired admixture, such as water, oil or other materials in fluid, liquid or semi-liquid state or condition. The liquid or liquids and substance or substances are fed into the machine preferably simultaneously and continuously.

The invention consists essentially in the employment of a plurality of cooperating, complementary, intermeshing or interacting worms or screws, preferably of opposite-hand, having equal differentials in pitch. These worms or screws are revolvably mounted within a suitable casing into which the substance or substances fed thereto undergoes or is subjected to the treatment herein described, and after said treatment discharged from the casing. The machine is provided with suitable driving mechanism, not shown. The adjacent cooperating intermeshing worms or screws are geared together so that they simultaneously revolve in the proper direction—at equal speeds.

As illustrating a specific manner in which the invention may be realized reference is made to the accompanying drawings forming a part of this specification, in which drawings,

Figure 1 is a plan view of the machine. In this view there is seen the casing into which the substance, or substances, is fed through a receiving opening or feed hopper 60 at one end and from which the mixed material is discharged at the other end; there is also seen a pair of opposite-handed intermeshing worms or screws located within and extending along the casing. 65

Figure 2 is a longitudinal vertical section of the machine clearly showing the receiving opening or feed hopper at one end of the casing; also showing one of the intermeshing worms or screws which extend from the receiving opening or feed hopper along and through the casing. This figure is a view taken as on the plane indicated by the line 2—2 of Figure 1 or of Figure 3 looking in the direction of the arrows; and 70

Figure 3 is a vertical transverse section which shows the casing in cross-section. It also shows the location and arrangement of the intermeshing worms or screws therein. This figure is a view taken as on the plane indicated by the line 3—3 of Figure 1 or 75 of Figure 2 looking in the direction of the arrows.

Referring now to the drawings in detail, 1, 1 designates two parallel channel members 85 which may be referred to and considered as main frame members or supports for the machine. The casing of the machine is designated by 2 and comprises a throat member or portion 3 and a tubular body member 90 or portion 4. The throat member or portion 3 has a hopper 27 that provides the feed opening or receiving opening through which the substance to be treated enters. A plurality of cooperating intermeshing or interacting worms or screws—a pair of such screws 5, 5—are located within and extend along the tubular body member or portion 4. These worms or screws 5 are preferably opposite-handed; in other words, the flights or spirals 6 on one screw slope in an opposite direction to that of the flights or spirals 7 on the companion screw, as is readily seen from an inspection of Figure 1. These worms or screws are geared together by means of gear-wheels 8, 8, so that when the screws rotate they turn in opposite directions. 100

The throat member or portion 3 is secured to the channel members or main frame members 1 at one end in any suitable manner, as 110 by bolts 9. At the other end of the channel members or main frame members 1 there is

secured in any suitable manner a bearing member 10 which may be relied upon to support the ends 11 of the shafts of the screws, to wit, the ends located at the discharge end of the machine. This bearing member 10, however, is mounted so that it can be readily removed and thereby permit an endwise or longitudinal movement of the screws from their operative position. At the charging end of the machine the intermeshing worms or screws 5 are held in place by suitable bearings 12 provided thereon. In the construction shown these bearings are carried by or provided in a projecting portion 13 on the throat member or portion 3. At the feeding end there is also provided a thrust bearing 14 for each of the worms or screws 5.

From the construction just described, it will be apparent that when the bearing member 10 is removed the screws can be readily taken from the machine by being moved in a longitudinal direction, indicated by the arrow 15. It will also be observed that in the construction shown the throat member or portion 3 is a fixed member and that the tubular body member or portion 4 is a movable member, being adjustable in a longitudinal direction in any suitable manner, as by screws 16, each of which screws extends through and is revolvably mounted upon an ear portion 17 of the throat member 3. These screws 16 are held in place against longitudinal movement relative to the ear portions by means of collars or shoulders 18 and 19. The threaded portion 20 of each screw extends through a corresponding lug or ear 21 threaded to receive it, said lug or ear extending from the tubular body member or portion 4. It will be readily apparent that by suitably turning the screws 16 the body member or portion 4 can be moved to any desired position along the intermeshing worms or screws 5, 5 and can be held by said screws 16 in adjusted position.

The tubular body member or portion 4 also has a second set of lugs designated as 22. The lugs 21 and 22 rest upon and are slidable along angle-irons or guides 23 secured in any suitable manner to parallel channel members or main frame members 1, with the result that the weight of the tubular member or portion 4 and any load therein is ultimately supported by means of the lugs 21 and 22 and angle-irons or guides 23 upon the channel members or main frame members 1. In cross-section, the interior contour of the tubular member or portion 4 is bicylindrical or in the form of the numeral 8 and in each lobe of the numeral there is located one of the intermeshing screws, as is readily apparent from an inspection of Figure 3. The tubular body member or portion 4 has a reduced portion or neck 24 that enters and fits a correspond-

ing socket portion 25 on the throat member or portion 3, and the construction is such as to permit or allow the tubular body member or portion 4 to be moved longitudinally to any desired position along the intermeshing worms or screws 5 and at the same time to maintain the throat member 3 and tubular body member 4 in cooperation to constitute a casing for the machine. The oil, pitch, water, steam or other material in fluid, liquid or semi-liquid state or condition is conveyed to the casing in any suitable manner, as through valve-controlled pipes 26.

From what has preceded, it will be apparent that the throat member or portion 3 and the tubular body member or portion 4 constitute the casing of the machine, and while these two members or portions have been shown as separate members still it will be manifest that in some instances it will be practicable to make said members integral. However, in the specific form of the invention these members or portions 3 and 4 have been made separate so as to permit of the longitudinal adjustment of the body member 4 along the intermeshing screws 5 without necessitating the change of position of the throat member and of the bearing members carrying the shafts on the intermeshing worms or screws. As the worms or screws 5 have equal differentials of pitch, in other words, are constructed so that in passing from the charging end of the machine toward the discharging end thereof the pitch of the flights or spirals of the worms or screws gradually decrease, it will be apparent that a movement of the body member or portion 4 along the screws in effect constitutes an extension of the body member and can be relied upon to control the degree of mixing of the material and substances within the machine and also the degree of pressure to which the materials and substances are subjected.

The operation of the machine is as follows:

Materials or substances, such as uniformly but partially distilled coal residue in finely divided or pulverized condition, enter through the receiving opening of the feed hopper 27 and are engaged by the spirals or flights 6 and 7 of the intermeshing worms or screws 5. The admixture is fed to the material in the machine in any suitable manner, either with the entering material to be treated, if the admixture at that time is in solid form, or through the pipes 26, if it is then in a form to flow through the pipes. Should the admixture be in the form of hard pitch, then heat is supplied thereto in order to melt it, as by injecting superheated steam in the mixture through one or more of the pipes 26; or even by the direct application of heat to the exterior of the casing. As a matter of fact, one

of the pipes 26 could be relied upon to supply oil or pitch in liquid or semi-liquid form, while another pipe 26 might be relied upon to supply steam, either saturated, 5 dry or superheated; or, a third pipe might be employed for the purpose of tempering the mixture. As the intermeshing worms or screws 5 are turned they operate so as to subject the material and substances 10 to the casing to a mixing action and so as to also subject the material to an increasing degree of compression as the substances travel from the charging end of the machine toward the discharging end thereof, 15 and particularly as the substances pass through the tubular body portion 4. The degree of mixing and compressing to which the substances are to be treated is controlled preferably to a certain extent by 20 the position of the tubular body member 4 along the worms or screws 5. In other words, when the tubular body member 4 occupies its innermost position or the position nearest the throat member 3 the degree of mixing and compressing to which 25 the substances are subjected in passing through the machine is less than is the case when the body member 4 occupies its outermost position and the degree of mixing and compressing is preferably controlled to a 30 certain extent by the intermediate position for the tubular body member 4. The length of the intermeshing worms or screws, the number of the spirals or flights, and the differentials in pitch should be determined 35 according to the nature of the substance or substances to be treated, the degree of mixing desired, and also the degree of compression desired. As previously indicated, 40 heat can be applied to the exterior of the casing in order to supply any added heat necessary or desirable for carrying out or facilitating the fluxing and mixing operation in the machine.

45 The improvements herein set forth are not limited to the precise construction and arrangement shown and described for they may be embodied in various forms and modifications without departing from the 50 spirit and scope of the invention.

What is claimed is:

1. A mixing and fluxing apparatus comprising a tubular casing member and a pair of cooperating intermeshing and interacting worms or screws therein, said casing having a receiving opening at one end and a discharge opening at the other end, said tubular casing being in cross-section in the form of the numeral 8, there being one of said screws in each lobe of the 8, which screws are characterized by having the pitch of the flights or spirals on each gradually decreasing in passing from the receiving opening toward the discharge opening, the apparatus 65 having means whereby said screws rotate

in the proper direction relative to each other, and also having means for effecting a relative longitudinal adjustment between the screws on the one hand and the effective body portion of the casing which co-operates 70 with the screws on the other.

2. A mixing and fluxing apparatus comprising a casing having a longitudinally extending tubular portion the interior of which is bicylindrical in cross-section, a pair of 75 cooperating interacting and intermeshing worms or screws located in said bicylindrical portion, which screws are opposite-handed and so constructed that they have equal differentials in pitch, gearing whereby 80 said screws must turn in opposite directions relative to each other, and means for adjusting said tubular body portion longitudinally along the screws and for holding said screws in adjusted position. 85

3. A mixing and fluxing apparatus comprising a casing having a longitudinally extending tubular portion and cooperating interacting and intermeshing worms or screws located in said tubular portions and which 90 screws have equal differentials in pitch, gearing whereby said screws must turn in the proper direction relative to each other, and means for effecting a change in the length of said tubular body member along said 95 worms or screws.

4. A mixing and fluxing apparatus comprising a casing having a longitudinally extending tubular portion the interior of which is in cross-section in the form of the numeral 100 8, a pair of cooperating interacting and intermeshing worms or screws, there being one of said screws located in each lobe of the 8, gearing whereby each screw must turn in the proper direction relative to the other, 105 and means for causing a change in the effective length of that portion of the casing which extends longitudinally along the screws.

5. A mixing and fluxing apparatus comprising a casing having a fixed throat member or portion provided with a hopper, a longitudinally adjustable tubular body member or portion the interior of which is bicylindrical in cross-section, a pair of cooperating interacting and intermeshing worms or screws extending from the throat member and located in said bicylindrical portion, which screws each have a differential pitch, means for effecting the longitudinal adjustment of said tubular body member of portion along the screws, and piping for supplying material in fluid, liquid, or semi-liquid state to the substances within the casing. 110 115 120 125

This specification signed the 5th day of November, A. D. 1920, and 12th day of November, A. D. 1920.

PAUL L. MATHEWS.
